UNITED STATES PATENT OFFICE.

WILLIAM H. LLOYD, OF CHICAGO, ILLINOIS, ASSIGNOR TO CRANE COMPANY, OF CHICAGO, ILLINOIS, A CORPORATION OF ILLINOIS.

DESIGN FOR A LAVATORY.

SPECIFICATION forming part of Design No. 37,256, dated December 6, 1904.

Application filed March 9, 1904. Serial No. 197,364. Term of patent 7 years.

To all whom it may concern:

Be it known that I, WILLIAM H. LLOYD, a citizen of the United States, residing at Chicago, county of Cook, and State of Illinois, have invented a new, original, and ornamental Design for a Lavatory, of which the following is a specification, reference being had to the accompanying drawings, forming part hereof.

Figure 1 is a top plan view of the lavatory, showing my new design;

Figure 2 is a perspective view of the same. What I claim as new, and desire to secure by Letters Patent, is the ornamental design for lavatory as shown.
